DESIGN FOR AN ELECTRIC FRUIT JUICER

Harry L. Stiles, Chicago, Ill., assignor to Chicago
Electric Manufacturing Company, Chicago, Ill.,
a corporation of Illinois

Application October 10, 1947, Serial No. 141,855

Term of patent 14 years

(Cl. D89—1)

To all whom it may concern:

Be it known that I, Harry L. Stiles, a citizen of the United States, residing at Chicago, Cook County, State of Illinois, have invented a new, original, and ornamental Design for an Electric Fruit Juicer, of which the following is a specification, reference being had to the accompanying drawing, forming a part thereof.

Fig. 1 is a side elevational view of an electric fruit juicer, showing my new design;

Fig. 2 is a plan view of the fruit juicer;

Fig. 3 is a front elevational view of the fruit juicer; and

Fig. 4 is a plan view of the body portion of the fruit juicer having the upper bowl portion removed with the drive shaft being shown in section.

I claim:

The ornamental design for an electric fruit juicer, as shown.

HARRY L. STILES.
